HENRY SCHREINER, OF PHILADELPHIA, PENNSYLVANIA.

Letters Patent No. 85,137, dated December 22, 1868; antedated November 3, 1868.

IMPROVED CAR-REPLACER.

The Schedule referred to in these Letters Patent and making part of the same.

To all whom it may concern:

Be it known that I, HENRY SCHREINER, of the city of Philadelphia, in the State of Pennsylvania, have invented a new and useful Improvement in the Portable Car-Replacer; and I do hereby declare that the following is a full, clear, and exact description of the construction and operation of the same, reference being had to the accompanying drawings, making a part of this specification, in which—

Figure 1 is a plan view of the said improved replacer applied to a railway-track;

Figures 2 and 3, transverse sections of the replacer, on the dotted lines *x w* and *x y*, respectively, of fig. 1; and

Figure 4, a side elevation, showing the manner of applying the adjusting-wedge.

Like letters of reference indicate the same parts when in the different figures.

The object of my improvement is to afford or produce a simple, durable, easily-applied, and more reliable and certain means for replacing a car or locomotive-engine upon a railway-track; and

The nature of my invention consists, substantially as hereinafter shown and described, in the peculiar construction of a pair of sloping iron plates, each provided with two elevated ridges or bearings, to guide the respective wheels of the car or locomotive to their proper positions on the track-rails, with a groove and a spike-hole, to keep them in their said positions upon the rails, and with an adjusting-wedge to render them steady and firm on rails of different heights.

Referring to the drawings—

A B, represent the plate for the outside of the track, and *C D*, the plate for the inside of the track, both being applied to the respective rails *E* and *F*.

a b', the elevated ridges or bearings of the plate *A B*.

c d', the elevated ridges or bearings of the plate *C D*.

G G, the respective adjusting-wedges of the two plates.

H H, the respective grooves, and

I I, the respective spike-holes of the same.

The plates, with their elevated ridges or bearings, grooves, and wedge-seats, are each intended to be made of iron cast in one solid piece, and to be about two feet long, and about fifteen inches wide at their rear or thinner ends, and about eight or ten inches wide at their forward or thicker end.

In the under side of the thicker end of each, the groove *I* is made so as to readily fit over upon the rail *E* or *F*, which supports it, while the thin rear end of the said plate rests upon the ground beside the rail,

thus producing an inclined plane, reaching from the ground upward to and upon the top of the rail.

The elevated bearing *b'* and ridges *c d'*, receive and fend off the flanges of the wheels of both sides of the car or locomotive, as they come in contact with them, and thus guide the wheels up the respective planes; the said wheels on each side of the car rolling upon their flanges, until they reach nearly to the top of the planes, where the bearing *b'* is made thicker or more elevated, so that it lifts the wheel on that side by its tread, in such a manner as to clear its flange from the flat plane *b''*, and thus allow the tread of the wheel to bear only upon the flat plane *b'*, and thus to diminish its speed in relation to the opposite wheel, (of the same axle,) which rolls upon its flange, and in this manner cause the forward end of the car to turn toward the left, so as to come more into line with the track before it drops upon the track-rails. (See the faint lines in fig. 1.)

In applying these plates *A B* and *C D*, to the track-rails *E F*, the wedges *G G* are to be either pushed inward, or drawn outward, in their respective seats under the plates, until the latter become steady or firm; and, when necessary, an iron pin or spike should be driven through the respective holes *I I* into the ground, in order to keep the inner sides of the rear ends of the plates in close contact with the sides of the respective rails.

In the drawings, the plates are shown as in positions for replacing a car from the left sides of the track-rails. In order to replace from the right side, the plates must be changed and reversed upon the track-rails, and then the car backed on, but it is intended, when locomotives are used, to have two pairs of plates, a right and a left-hand set, to be carried on each train.

What I claim as my invention, and desire to secure by Letters Patent, is confined to the following, *i. e.:*

A portable car-replacer, consisting of the pair of sloping plates *A B* and *C D*, for the right and left rails, respectively, of a track, the plate *A B* having the elevated ridges or bearings *a b'*, and the plate *C D* having the elevated ridges or bearings *c d'*, and each plate having the rail-groove *H*, and the adjusting-wedge *G*, all the said parts being constructed and arranged in relation to the slopes of the respective plates *A B* and *C D*, as shown and described for the purposes specified.

HENRY SCHREINER.
